C. E. GODLEY

SIGNAL LAMP

Filed June 24, 1922.

INVENTOR
Charles E. Godley

Edward N. Pagelsen,
ATTORNEY

UNITED STATES PATENT OFFICE.

CHARLES E. GODLEY, OF DETROIT, MICHIGAN, ASSIGNOR TO EDMUND & JONES CORPORATION, OF DETROIT, MICHIGAN, A CORPORATION OF NEW YORK.

SIGNAL LAMP.

Application filed June 24, 1922. Serial No. 570,870.

To all whom it may concern:

Be it known that I, CHARLES E. GODLEY, a citizen of the United States, and residing at Detroit, in the county of Wayne and State of Michigan, have invented a new and Improved Signal Lamp, of which the following is a specification.

This invention relates to the construction of a lamp for the rear ends of motor vehicles and its object is to provide a simple and effective combined tail-lamp and rear signal lamp which can be made at low cost, and which may be used to illuminate the roadway, rearwardly and laterally, of the vehicle.

In the accompanying drawing Fig. 1 is a front elevation of this improved signal lamp. Fig. 2 is a section on the line 2—2 of Fig. 1. Fig. 3 is a section on the line 20 3—3 of Fig. 2. Fig. 4 is a plan of an insert which constitutes the separate compartment for the signal lamp. Fig. 5 is a section on the line 5—5 of Fig. 1. Fig. 6 is a bottom plan of a connector plug. Fig. 7 is a section on the line 7—7 of Fig. 3.

Similar reference characters refer to like parts throughout the several views.

The body of this lamp has a back 1, sides 2, and 3 which merge into the semi-cylindrical top 4 and bottom 5. The front edge of the body is bent out to form the flange 6 which ends in an end 7 parallel to the sides, top and bottom of the body. The lamp may be attached to any desired bracket 30 or support by means of bolts 8 mounted in the back 1. An opening 9 may be cut in the bottom 5 to permit light to fall on a license plate, this opening being covered by a small sheet 10 of celluloid which is held 40 in position by the ears 11.

A cylindrical insert consisting of the shell 14, back 15 and front flange 16 may be mounted in the upper part of the body, the body and the insert having inter-engaging 45 ribs 17 and 18 respectively. The flange 16 may be formed with a groove to receive the packing cord 19 against which the lens 20 is pressed by the door, the cord preventing entrance of dust and also preventing the 50 lens from rattling.

Mounted on the lower portion of the shell 14 is a connector tube 22 formed with bayonet slots 23 to receive the pins 24 on the

bases 25 of the light bulbs 26 and 27. The two bases have central projections 28 adapted to be engaged by the spring contacts 29 carried by an insulating plug 30. These contacts have transversely corrugated ends 31, or are otherwise deformed to receive these projections 28 and are thereby held 60 in position. A short thimble 33 is attached to the side of the body at an opening therein to receive this plug and the thimble is preferably formed with a rib 34 adapted to enter the groove 35 in this plug to insure 65 the plug being inserted properly. The connector tube 22 is preferably lined with a shell 36 of insulating material to prevent the contacts 29 from touching the sleeve. The bases of the lamp bulbs are grounded on 70 this sleeve.

Wires 38 and 39 extend into the plug and are secured in eyes in the ends of the contacts 29 by means of screws 40. The well known cap 41 may be attached to this plug 75 to protect the wires. It will be noticed that these wires are at right angles to the thimble 33 so that a pull on the wires is not liable to disengage the plug and the contacts.

The flange 6 on the body below the insert is also grooved to receive the packing cord 43 against which the lens 44 is held by the cover. The upper lens 20 is preferably circular while the upper part of the lower lens is cut away to fit the upper lens. The lower lens is preferably convex outward as shown in Fig. 2. The cover or door is formed with a flange 45 to fit around the edge 7 of the body and with an inwardly curved edge 46 to engage the two lenses. It also comprises a preferably semi-cylindrical cross piece 47 which extends over the adjacent edges of the two lenses.

Any desired means may be employed to secure the cover in position. I prefer to 95 bulge out the sides 2 and 3 and secure nuts 48 in the spaces thus formed by soldering or welding, which nuts are adapted to receive the screws 49 which extend through the cover.

Referring now to the insert it will be noticed that its shell 14 is formed with two inwardly extending circumferential beads or ribs 50 and 51 and that a reflector 53 is mounted therein and provided with a flange 54 to fit between these ribs. These ribs are so

inclined to the axis of the shell 14 that the reflector 53 will project the light downward and laterally of the line of the vehicle. It is usually desirable to illuminate the road-
5 way at the left of the vehicle when that is being backed and for this reason I prefer to have the reflector mounted in the manner shown in Figs. 2 and 4.

The switch mechanism for these lamp 10 bulbs may be of any well known construction and none is therefore shown. Any well known switch may be connected into the circuit to the lower light bulb. I prefer to connect two self opening switches in parallel into the circuit to the upper bulb. One of these switches will be connected so that it is closed when the control lever is shifted into "reverse" position so that the upper light will illuminate the roadway as a back-
15 light when the vehicle is run rearwardly. The other switch may be so connected as to be closed whenever either the clutch lever or brake lever is pushed in, as is now the case with most "stop" lamps. Drivers
20 differ as to which is preferable.
25

I claim:-

1. In a signal lamp, the combination of a case, a cover therefor comprising two lenses and a frame to secure them to the case, a 30 cylindrical shell mounted in the case, a connector tube mounted in said shell and having an aperture outside the shell, a light bulb mounted in each end of the connector tube opposite said lenses and having a central contact at the inner end of its base, an insulating plug mounted in one wall of the case, a pair of contacts extending therefrom into the connector tube to engage the contacts on the light bulbs, and conductors connecting to the contacts mounted in said plug.
40

2. In a signal lamp, the combination of a case having parallel sides and cylindrical ends, a cover therefor comprising two lenses and a frame to secure the lenses to the case, a cylindrical shell mounted in the case, a connector tube mounted in said shell and having an aperture outside of the shell, a light bulb mounted in each end of the connector tube and having a contact on the inner 45 end of its base, an insulating plug mounted on one of the sides of the case, a pair of resilient contact fingers mounted on said plug and extending between the contacts on the bases of the light bulbs and engaging
50 the same, and a pair of conductor wires connecting to said resilient contacts.
55

3. In a signal lamp, the combination of a case, a pair of lenses in substantially the same plane and a support therefor attached to the case, a connector sleeve mounted in the case substantially parallel to the lenses and having an opening between its ends, a light bulb in each end of the sleeve opposite the lenses and having contacts at their
60 inner ends, a tubular member mounted in
65

said case at right angles to said connector tube, resilient fingers mounted in said tubular member and extending into the opening in the connector sleeve, and means detachably mounted in said tubular member 70 adapted to receive circuit wires and cause an electrical connection between them and said fingers.

4. In a signal lamp, the combination of a case having parallel sides and cylindrical ends, a cover therefor comprising two lenses and a frame to secure the lenses to the case, a cylindrical shell mounted in the case, a connector tube mounted in said shell, and having an aperture outside of the shell, a 75 light bulb mounted in each end of the connector tube and having a contact on the inner end of its base, and means embodying resilient fingers adapted to engage said contacts to conduct current to said contacts.
80

5. In a signal lamp, the combination of a case having parallel sides and cylindrical ends, a cover therefor comprising two lenses and a frame to secure the lenses to the case, a cylindrical shell mounted in the case, a reflector in the rear end of the shell, said shell being formed with inwardly projecting ribs to secure the reflector in position, a connector tube mounted in said shell and having an aperture outside of the shell, a light bulb mounted in each end of the connector tube and having a contact on the inner end of its base, an insulating plug mounted on one of the sides of the case, a 90 pair of resilient contact fingers mounted on said plug and extending between the contacts on the bases of the light bulbs and engaging the same, and a pair of conductor wires connecting to said resilient contacts.
95

6. In a signal lamp, the combination of a case having parallel sides and cylindrical ends, a cover therefor comprising two lenses and a frame to secure the lenses to the case, a cylindrical shell mounted in the case, a reflector mounted in the rear end of the shell and having its axis extending downwardly and laterally of the axis of the shell, a connector tube mounted in said shell and having an aperture outside of the shell, a light bulb mounted in each end of the connector tube and having a contact on the inner end of its base, and insulating plug mounted on one of the sides of the case, a pair of resilient contact fingers mounted on said plug and extending between the contacts on the bases of the light bulbs and engaging the same, and a pair of conductor wires connecting to said resilient contacts.
105

7. In a signal lamp, the combination of a case having parallel sides and cylindrical ends, a cover therefor comprising two lenses and a frame to secure the lenses to the case, a cylindrical shell mounted in the case, a connector tube mounted in said shell and having an aperture outside of the shell, a 110
115
120
125
130

light bulb mounted in each end of the connector tube and having a contact on the inner end of its base, an insulating plug mounted in one of the sides of the case, a pair of resilient contact fingers mounted in said plug and extending between the contacts on the bases of the light bulbs and engaging the same, and a pair of conductor wires connecting to said resilient contacts, the inner ends of the resilient contacts being deformed to receive the contacts on the light bulbs whereby the insulated plug may be retained in position.

CHARLES E. GODLEY.
